ELECTRIC MOTOR STARTER

Filed Jan. 7, 1928

FIG. 1.

UNITED STATES PATENT OFFICE

WILLIAM T. HOLMES, OF BALTIMORE, MARYLAND; DAISY N. HOLMES, EXECUTRIX OF SAID WILLIAM T. HOLMES, DECEASED, ASSIGNOR TO MONITOR CONTROLLER COMPANY, OF BALTIMORE, MARYLAND, A CORPORATION OF MARYLAND

ELECTRIC-MOTOR STARTER

Application filed January 7, 1928. Serial No. 245,156.

This invention relates to electric motor starters of the class wherein the cutting out of the starting resistance is controlled by current flow in the armature circuit of the motor. 5 In the patent to Whittingham, No. 1,135,870, dated April 18, 1915, is shown a starter in which a centrally pivoted contactor is rocked to closing position by a magnet having its coils connected across the line in a circuit independent of the armature circuit of the motor, and a magnet, having its coils in series with the armature circuit, acts in opposition to the first mentioned magnet and prevents the closure of the contactor until the armature current falls to a predetermined value. 10 This starter operates satisfactorily under all working conditions; but under very unusual conditions, as may be brought about by temporary grounds or short circuits on the supply circuit, the voltage at the terminals of the magnet which rocks the contactor to closed position, may be lowered to such an extent that it will not overpower the series magnet and close the contactor when the current in 15 the coils of the series magnet is at the predetermined value where, under ordinary conditions, the contactor would close. In the present invention, the main and auxiliary contactors are moved to their closed positions and held in such positions by magnets, the coils of which are connected across the line, but they are not acted upon or retarded by series coils, as in the patent referred to, and therefore will be held in their closed positions even 20 with a very large drop in line voltage. The timing of the closure of the auxiliary contactors, in the present invention, is attained by the use of relays, each having a magnet connected in shunt to a part of the starting resistance, whereby the relay is controlled by the armature current. Each relay controls the circuit of a magnet for closing an auxiliary contactor and operates to close said circuit when the armature current falls to a predetermined value. 25 By this arrangement, the time of closure of the auxiliary contactors is controlled by the armature current, but there is no magnetic force applied to the contactors tending to open the same, and hence the magnets which close the contactors will hold them

in closed positions, even with a large drop in voltage in the supply circuit.

In the accompanying drawing,

Fig. 1 is a diagrammatic view, illustrating the invention in its preferred form; and

Fig. 2 is a similar view, showing a modified form of starter.

Referring to Fig. 1 of the drawing, L and L' indicate the supply wires leading from a power source, S indicates the starter, and M indicates a motor to be controlled by the starter. 30 The starter comprises the starting resistance R, a main contactor *a*, for closing the circuit through the resistance, and auxiliary contactors *b* and *c*, for cutting out the resistance. These contactors are adapted to be closed by magnets 1, 2, and 3, which magnets are mounted upon metal bases 1^a, 2^a, and 3^a, respectively. The starting resistance is connected to the bases of the magnets, as shown, thus dividing the resistance into sections *r* and *r'*. The armature circuit extends from the starting resistance by conductor 4 to the armature *m*, and thence to the supply wire L'. The field *f* of the motor is connected to the supply wire L', and also by conductor 5 to the base 1^a of the magnet 1. The contactors *a*, *b*, and *c* are adapted to engage stationary contacts 6, 7, and 8, respectively, which contacts are connected by conductor 9 to the supply wire L, as shown. The contactors are pivotally mounted upon the magnet bases, as shown, and are therefore electrically connected to said bases. 50

It will be seen that when the contactor *a* closes against the contact 6, current will flow from the supply wire L, through the contactor *a* and the base 1^a to the field *f* of the motor through the conductor 5, and also to the armature of the motor through the entire resistance R. When the auxiliary contactor *b* closes, current will flow from the stationary contact 7 through contactor *b* and magnet base 2^a to the section *r'* of the starting resistance, and thence to the motor, thus short circuiting the section *r* of the starting resistance. When the contactor *c* closes, current will flow through stationary contact 8 and this contactor through base 3^a directly to the motor, thus short circuiting the section *r'* of the resistance. 55 The coils of the magnets 1, 2, and 3, when

in circuit, are connected across the line and receive the full line voltage. The circuit of the magnet 1 is controlled by a hand switch *h*, so that immediately upon closure of the switch the contactor *a* will close; but the circuits of the magnets 2 and 3 of the auxiliary contactors are controlled by relays *d* and *d'*, so that said contactors close in succession at predetermined current values in the armature circuit of the motor.

The circuits of the relay magnets 10 and 11 are connected in shunt to portions of the starting resistance. The relay *d* comprises the magnet 10, mounted upon a suitable base 10^a, connected to the base 1^a, and an armature 12, which is constantly urged away from the magnet by a spring 13. This armature is adapted to engage a stationary contact 14, but is normally held out of engagement with said contact and in close relation to the pole of the magnet 10 by an extension *a'* on the main contactor *a*. The relay *d'* is similar to the relay *d*, and its armature 15 is adapted to engage a stationary contact 16, but is normally held out of engagement with said contact by an extension *b'* on the auxiliary contactor *b*. The base 11^a of the relay magnet 11 is electrically connected to the base 2^a of the magnet 2.

The switch blade 18 of the switch *h* is connected by conductor 19 to the supply wire *L*, and this blade is adapted to engage stationary contacts 20 and 21 practically at the same time. A conductor 22 connects the contacts 21 with the coils of the shunt magnet 1, and these coils are connected by conductor 23 to the supply wire *L'*. Hence, when the switch *h* is closed, the magnet 1 will be energized and the main contactor will engage the stationary contact 6 and close the armature circuit through the entire resistance. A conductor 24 connects the contact 20 with the coil of the relay magnet 10, and a conductor 25 extends from this coil to an adjustable contact member 26, which engages the resistance section *r*. Hence, when the switch *h* closes, the magnet of the relay *d* will be strongly energized by current flowing through the circuit just traced to the resistance and thence to the motor. The contactor *a*, in closing, releases the armature 12; but the current flowing through the magnet 10 holds the armature 12 away from the contact 14 until the current in the coil of the magnet 10 falls to a predetermined value, when the magnet releases the armature and the latter is moved by the spring 13 into engagement with the contact 14.

It is to be noted that when the switch *h* is closed, the magnet coils of the relay *d* are connected in shunt to that portion of the starting resistance which is included between the base 1^a and the point where the adjustable arm 26 engages the resistance. Hence, the armature current will divide between said portion of the resistance and the coil of the

magnet 10, and the latter will hold the armature 12 until the current in the armature circuit of the motor falls to a predetermined degree, when the armature 12 will move away from the magnet 10 and engage the contact 14. The time of release of the armature 12 by the magnet may be varied by adjustment of the spring 13 or adjustment of the arm 26 to include more or less of the starting resistance in parallel with the coils of the relay magnet.

When the armature of the relay *d* engages the contact 14, it closes a circuit through the shunt magnet 2 of the auxiliary contactor *b*, and also a circuit through the coil of the magnet 11 of the relay *d'*. Thus, the contact 14 is connected by conductor 27 to the coil of the magnet 2, and thence by conductors 28 and 23 to the supply wire *L'*. The circuit of the magnet 11 of relay *d'* extends from the contact 14, through conductor 27 to conductor 29, thence through the magnet coil and by conductor 30 to the adjustable arm 31 which engages the section *r'* of the starting resistance. It will be seen that when the relay armature 12 engages the contact 14, current will flow through the main contactor *a* to the base 10^a of the relay *d*, thence through armature 12 to the contact 14, from whence current will flow through the coils of magnet 2 and through the coils of the magnet 11 of relay *d'*. The auxiliary contactor *b* will be immediately moved to the closed position by the magnet 2, and the extension *b'* of the contactor will be moved away from the armature 15 of the relay. The main contactor will cut out the section *r* of the starting resistance, and the coils of the relay magnet will remain in parallel with a part of the section *r'* of the starting resistance. When the armature current falls to a predetermined value, the relay *d'* will release its armature 15 and the latter will engage the contact 16, thereby closing the circuit through the magnet 3, which controls the auxiliary contactor *c*. This circuit extends from the contactor *b*, through the base 11^a of the relay to the armature 15, thence to contact 16, thence through conductor 32 to the coils of magnet 3, and thence through conductors 33 and 23 to the side *L'* of the supply circuit. Upon the closure of this magnet circuit the contactor *c* will instantly close and short circuit the section *r'* of the starting resistance.

From the foregoing, it will be seen that upon closure of the manually operable switch *h*, the main contactor *a* will close instantly, but the time of closure of the auxiliary contactors will be determined by the volume of current in the armature circuit. The shunt connected magnets 1, 2, and 3, which close the contactors, may be made of such strength that they will hold the contactors closed even with a very considerable drop in voltage, as may occur with grounds and short circuits on

the line, or from other causes. Thus, in the 5 starter described, the cutting out of the starting resistance is controlled by the current in the armature circuit, but the contactors are held in their closed positions by magnets which are not affected by fluctuations of the 10 armature current, and hence they will stay closed under all working conditions of the motor and will be released only when there is a very heavy drop in voltage on the line, or when the switch h is opened to stop the motor.

When the switch h is opened, it will interrupt the circuit of the magnet 1 and the 15 latter will release the main contactor, and it will also open the circuit through the relay magnet 10, and current will thus be cut off from the motor. The main contactor, in opening, will move the relay armature 12 20 away from the contact 14 and into close relation to the magnet 10, thus interrupting the circuit through the magnet 2 of the auxiliary contactor b , and also through the relay magnet 11. The contactor b will move the relay 25 armature 15 out of engagement with contact 16, thus interrupting the circuit through the magnet 3 of contactor c , and the latter will fall back to its normal position.

In Fig. 2 of the drawing, I have shown a 30 modified form of starter, comprising a main contactor and an auxiliary contactor, in which the switch arm of the current-controlled relay is not held in normal position mechanically by a contactor.

Referring to Fig. 2, S' indicates the starter and M indicates a motor controlled by the 35 starter. A main contactor a^2 is adapted to be closed by a shunt magnet 35, and the auxiliary contactor c^2 is adapted to be closed by a shunt magnet 36. A relay d^2 controls the 40 circuit of the magnet 36. The starting resistance is connected to the bases 35^a and 33^a of the magnets 35 and 36, respectively, and the field circuit 37 of the motor is connected 45 to the base 35^a and to the supply wire L' , as shown. The contactors a^2 and c^2 are adapted to engage fixed contacts 38 and 39, respectively, which latter are connected by a wire 40 to the supply wire L . A conductor 41 leads 50 from the supply wire L to a relay contact 42, which is adapted to be engaged by the relay armature 43, but the latter is normally held out of engagement with said contact by an adjustable spring 44. A circuit extends from 55 conductor 41, through a normally open push button switch P , by way of conductors 43 and 44 to the coils of relay magnet 45, and thence by conductor 46 to adjustable contact 47, which engages the resistance section r^3 60 at a point intermediate the bases 35^a and 36^a. It will be evident that when the push button switch P is closed, current will flow from the supply wire L through the circuit just traced to the resistance r^3 , and thence through the 65 motor armature m to the supply wire L' , and

the magnet 45 will be energized. This magnet will move the switch arm 43 out of engagement with a contact 48 and into engagement with the contact 42. When the switch arm 43 engages contact 42, a circuit will be completed through the magnet 35 of the main contactor as follows: from supply wire L , through conductor 41 to switch arm 43, thence through the base 49 of the relay magnet to conductor 50, thence through conductor 51 to a normally closed stop push button switch 52, thence through conductor 53 to the coils of magnet 35, thence through conductor 54 to the side L' of the supply circuit. The magnet 35 will cause the main contactor a^2 to close, and when said contactor closes, it will complete the motor circuits and also complete holding circuits through the magnets 45 and 35, so that these magnets will remain energized after the operator releases the push button switch P . Thus, when the main contactor closes, it connects the side L of the supply circuit to contact 55, which is connected by conductor 56 to conductor 44, and hence current from the supply wire L 75 can flow through the contactor and conductor 44 to the relay magnet 45 after the start push button P has been released, and the relay magnet will hold the switch arm 43 in engagement with contact 42. The main contactor will also connect a contact 57 with the supply wire L , and current will flow from 80 said contact through conductors 58 and 51 to the stop push button switch 52, thence through the shunt magnet 35 to the supply wire L' . The magnet 35 will therefore be 85 energized even after the relay magnet 45 releases the switch arm 43.

By reason of the circuits thus traced, the closure of the start push button switch will 90 cause the relay switch to close a circuit through the magnet of the main contactor, and the latter will immediately close the motor circuits and the magnet of the coils of the relay switch will be included in shunt to that portion of the starting resistance which lies between the bases 35^a and the adjustable contact member 47. When the current in the armature circuit falls to a predetermined value, the relay magnet releases the switch arm 43, which is then drawn by the spring 44 into engagement with the contact 48. This completes a circuit through the shunt magnet 36 of the auxiliary contactor c^2 as follows: from the supply wire L , 95 through main contactor and conductors 58 and 50 to the base 49 of the relay, thence through switch arm 43 and contact 48 to conductor 59, thence through coils of magnet 36 and by conductors 60 and 54 to the supply 100 wire L' . The magnet 36 will cause the contactor c^2 to close, thus cutting out the starting resistance and at the same time closing a holding circuit through the magnet 36. This latter circuit extends from a contact 61, 105

which the main contactor engages, through conductor 62 to the wire 59, thence through coils of magnet 36 and by conductors 60 and 54 to the supply wire L'.

It will be evident that in the starter of Fig. 2, the time of closure of the auxiliary contactor, which cuts out the starting resistance, is controlled by the armature current, which divides between the relay magnet 70 and a part of the starting resistance. It will also be evident that when the circuits of the magnets 35 and 36 are made up the contactors will immediately close. These magnets may be wound so as to retain the contactors in 75 their closed positions, notwithstanding wide changes in the line voltage, and it will be evident that the magnets are not affected by fluctuations in armature current.

To stop the motor, it is merely necessary 20 to open the stop push button switch 52, which interrupts the circuit through the main contactor magnet and its contactor, in opening, opens the circuit through the relay magnet and the circuit which extends through the 25 base of said magnet to the magnet 36 of the auxiliary contactor. Hence, upon opening the stop push button switch, the parts will move to the position shown in the drawing.

What I claim is:

1. The combination with a supply circuit, 30 of a motor starter comprising a starting resistance, main and auxiliary contactors, magnets for closing the contactors, said magnets having circuits independent of the armature circuit of the motor, a relay comprising a switch member adapted to close the circuit of the magnet of the auxiliary contactor and a magnet having windings in parallel with part of the resistance for controlling 35 the movement of said member, said main contactor adapted to normally hold said member close to the relay magnet and to release said member and connect the same to the supply circuit when said main contactor closes.

2. The combination with a supply circuit, 40 of a motor starter comprising a starting resistance, main and auxiliary contactors, magnets for closing the contactors, said magnets having circuits independent of the armature circuit of the motor, a relay comprising a magnet having windings in parallel with part of the resistance and an armature normally held in close relation to the relay magnet by said main contactor, said main contactor, in closing, adapted to release said armature, and the latter adapted to close the circuit of the magnet of the auxiliary contactor when released by the relay magnet.

3. The combination with a supply circuit, 50 of a motor starter comprising a starting resistance, a series of contactors, magnets for closing the contactors, said magnets having circuits independent of the armature circuit of the motor, relays associated with the several contactors in the series except the last

one, each relay comprising a magnet having windings in parallel with part of the starting resistance and an armature normally held in close relation to the relay magnet by the contactor with which it is associated and adapted to be released when the contactor closes, and the armature of each relay adapted to close the circuit of the magnet of the next contactor in the series when released by the relay magnet.

4. The combination with a supply circuit, 55 of a motor starter comprising a starting resistance, a series of contactors, magnets for closing the contactors, said magnets having circuits independent of the armature circuit of the motor, relays associated with the several contactors in the series except the last one, each relay comprising a magnet having windings in parallel with part of the starting resistance and an armature normally held in close relation to the relay magnet by the contactor with which it is associated and adapted to be released when the contactor closes, and the armature of the relay associated with the first contactor in the series 60 adapted to close the circuit of the magnet of the next contactor in the series and also to close the circuit of the relay magnet associated with the latter contactor.

5. The combination with a supply circuit, 65 of a motor starter comprising a starting resistance, main and auxiliary contactors, magnets for closing the contactors, said magnets having circuits independent of the armature circuit of the motor, a relay comprising a switch member normally tending to close the circuit of the magnet of the auxiliary contactor and a magnet having windings in parallel with part only of the resistance for controlling the movement of said member, said main contactor adapted to normally bear against and hold said member in open position and to release said member and connect the same to the supply circuit when said main contactor closes.

In testimony whereof I hereunto affix my signature.

WILLIAM T. HOLMES.
